TRACTOR FILLING DEVICE

Ernst Loren Wallesar, Charles City, Iowa, assignor
to The Victor Corporation, Charles City, Iowa

Application April 29, 1939, Serial No. 270,878

5 Claims. (Cl. 226—116)

The present invention relates to a device for filling tractors and like internal combustion engines.

On the large farms of the Middle West it is extremely difficult to get a tractor to a filling station. Again, it would be a great waste of time to do so. Accordingly large drums of fuel are taken out into the field and the tractor refueled there.

10 The present device is one which utilizes the reduced pressure of the exhaust manifold to pump fuel from the supply drum into the fuel tank of the machine as may be observed from the drawing. The device is a relatively inexpensive one 15 to manufacture yet it is sturdy, satisfactory and serviceable.

The present invention presents two principal advantages. The first is intended to overcome the disadvantage in a device of this type wherein 20 the splash of fuel in tank gives rise to a heavy mist and droplet formation, the fuel is drawn into the intake manifold of the engine and stops or drowns it. At best the engine performance is greatly interfered with. The present device delivers much of the fuel under the surface of the 25 fuel already in the tank thus minimizing splash and droplet formation. Also the end of the delivery tube is positioned in a place remote from the holes through which the air above the fuel 30 is drawn into the vacuum tube leading to the intake manifold. Also these holes are positioned within the neck portion of the fuel tank where it is difficult for the droplets to get.

A second principal advantage of the present 35 device is the elimination of all clamps and holding means and the utilization of the pressure differential between the inside of the tank and the atmosphere to hold the filling device firmly in place. The use of a soft pliable gasket greatly 40 improves the seal and makes this second function possible.

In the drawing Fig. 1 is a plan view of the device with part broken away to show a valve control detail.

45 Fig. 2 is a sectional view along the line 2—2 of Fig. 1.

In the drawing element 1 is a body member which is disk shaped and provided with strengthening beadings 2 on its upper portion. Through 50 the upper portion 4 of body member 1 is channel 5 extending across the disk shaped body member 1. From one end of channel 5 leads a tube 6 which connects the channel 5 with a point of reduced pressure such as the intake manifold 55 of the engine. If desired a petcock valve or the like may be used to connect tube 6 with the intake manifold. Tube 6 is attached firmly to the disk 1 by means of nut 7 and threaded tubular member 8.

60 Into the opposite end of channel 5 is threaded

an intake adjusting screw 9 having a kerf 10 so that the position of the screw 9 may be easily adjusted with a screw driver. Leading downwardly from channel 5 is vertical channel 11.

In Fig. 2 it may be seen how the adjustment 5 of screw 9 controls the fluid flow from channel 11 to channel 5.

The lower part of disk 1 is provided with a depending portion 12 which is provided with an enlarged portion 13 connecting with channel 5. 10 The transition portion 14 between channels 5 and 13 is of frusto-conical shape and serves as a valve seat.

Vacuum tube 15 is of such diameter as to experience a force fit with channel portion 13. 15 Tube 15 is provided with a series of small intake holes 16 placed as near the depending portion 12 as is feasible.

Within tube 15 is a float 17 made up of three parts. The upper or head portion 18 of float 17 20 is shaped so as to mate with frusto-conical surface 14 and seat thereon. These two surfaces 14 and 18 form a valve. Middle portion 19 of float 17 is made of fine screen so as to catch as many 25 small fuel droplets as possible and prevent them from entering channel 5. The bottom portion of float 17 is a float member 20 made of cork or a sealed metal tube. The member 20 has sufficient buoyancy to carry portions 18 and 19 and cause the whole float 17 to rise with the fuel 30 level. Pin 21 prevents the float 17 from falling out of tube 15 when not immersed in fuel.

Depending portion 12 is provided with another vertical channel portion 22 into which fuel delivery tube 23 is forced. Fuel delivery tube 23 35 is substantially larger than vacuum tube 15 so that any fuel splash and droplet formation is kept well away from intake holes 16 or even the bottom of tube 15. Again by having delivery tube 23 long, much of the fuel may be delivered 40 under the surface of the fuel with a minimum of splash. If desired the end of tube 23 may be made flexible so as to rest on the bottom of tanks of different depths.

Near the upper end of tube 23 and as near portion 12 as feasible is provided a vacuum breaking hole 24 which is located on the opposite side of tube 23 from tube 15. Vacuum breaking hole 24 prevents the syphoning of fuel from the tank 50 when the valve 14—18 is closed or the engine stops. In many tractors the fuel tank is on top and several feet above the level of fuel in a drum resting on the ground.

Body member 1 is provided with a horizontal 55 channel portion 25 forming a continuation of channel portion 22. Fitting in the open end of channel portion 25, and experiencing a force fit therewith, is reduced end 26 of threaded coupling means 27. Threaded outer coupler 28 mates with 60

the threaded portion of coupler means 27. Gasket 29 makes a tight joint possible.

Hose 30 fits tightly over ferrule 31 which is held firmly against gasket 29 by outer coupler 28. The other end of hose 30 is placed in a drum of fuel to be pumped into the tractor tank.

The lower surface of body member 1 is provided with a soft gasket 32 intended to rest in sealing contact with upstanding neck 33 of tractor fuel tank 34.

In operation tube 6 is connected with the intake manifold of the tractor engine and the free end of hose 39 placed in a drum of fuel. Tubes 15 and 23 are placed into the open tank 34 and gasket 32 caused to firmly contact the lip neck 33 so as to form a complete air seal. With the engine running, the valve on the intake manifold to which tube 6 is connected, is opened. The atmospheric pressure differential causes air to flow from within tank 34 through tube 15, channels 13 and 5 and out through tube 6.

This flow unbalances the pressure on the surface of the fuel in the supply drum and causes it to flow through tube 30, channels 25, 22 and tube 23 into tank 34. When the fuel flows into the tank 34 splash results and mist or droplet formation would be drawn into tube 6 and drown the engine were it not for the construction of the device. Without any elaborate or expensive controls this danger is eliminated by placing hole 16 high up tube 15 and within neck portion 33. This greatly reduces the likelihood of drops of fuel entering the tube 6. Again the end of delivery tube 23 is far away from hole 16. Droplets rising through tube 15 from the bottom are caught by the eddies caused by screen 19. Since most of the fuel delivery is under surface, delivery droplet formation is minimized during the later stages of filling. However, the rise of float 17 in tube 15 brings it in front of holes 16 as the surface of the fluid nears them. This further blocks droplets entrained in the air.

The rate at which the fuel is pumped may be controlled by the relative position of screw 18 and channel 11. It is shown wide open for maximum delivery.

The fuel level in tank 34 rises until head 18 of float 17 meets surface 14 and closes channel 13. This stops fluid flow even though the tractor engine continues to run and so eliminates the danger of tank overflow with resultant wastage and fire hazard.

The intake valve is shut off or the engine is stopped. Leakage soon brings the interior of the tank to atmospheric pressure and a reverse flow of fluid in hose 30 takes place due to the longer arm leading to the supply tank. When the level in tank 34 falls to the hole 24 in fuel delivery tube 23 air is introduced into the line and the siphon effect is broken. It will be noted that hole 24 is also within the neck portion 33 of tank 34.

It is not usually necessary to provide holding means to fasten the filler to the tank 34 since the pressure differential within and without the tank is sufficient to do so. This brings out the importance of having gasket 32 soft. However, if it is desired to attach the filler permanently to the tank, suitable clamping or screw fastening means may be used.

The above description sets forth one form the invention may take. Others may be made without departing from the spirit thereof. For in-

stance tube 23 may be continued through the top of housing 1 and the hose 3 connected directly to it.

I claim:

1. In a filling device for the fuel tank of an internal combustion engine, a tank sealing member of sufficient size to cover the filling opening of the fuel tank of an internal combustion engine having an upstanding neck, a fuel delivery conduit means of such length as to deposit fuel well within said tank and adjacent the bottom thereof so that much of the filling is done under the surface of the fuel in the tank, an evacuating conduit, said conduit means having a hole through which gases may be removed, said hole being sufficiently close to said tank sealing member as to be within the upstanding neck of the fuel tank, whereby a minimum of spray and drops of fuel is carried to the engine through the evacuating conduit, automatic shut off means within said evacuating conduit adapted to rise as the level of the fuel in the tank rises and close said evacuating conduit when the fuel reaches a desired level, a portion of said shut off means being so positioned that the gases withdrawn from the tank pass around it during the final stages of filling whereby fuel droplets are trapped, said automatic shut off means comprising a screen float in said evacuating conduit, the screen of said float so arranged as to be in front of said hole during the final stages of filling so as to catch fuel droplets when the fuel level within the tank is close to said hole, a valve seat in said evacuating conduit arranged to receive the upper portion of said screen valve float.

2. In a filling device for the fuel tank of an internal combustion engine on tractors and the like, a tank sealing member of sufficient size to cover the filling opening of a fuel tank having an upstanding neck, a fuel delivery means supported by said tank sealing member, an evacuating conduit associated with said tank sealing means, said evacuating conduit having a hole therein substantially within the upstanding neck portion of said tank through which gases may be removed, perforated means within said evacuating conduit and positioned across said hole during the final stages of filling said tank whereby fuel droplets entrained in the gases being withdrawn are caught by said perforated member and returned to the tank and the uninterrupted operation of the motor is facilitated.

3. The combination set forth in claim 2, said perforated means comprising an automatic shut-off float the position of which is controlled by the fluid level in the tank, a valve seat in said evacuating conduit constructed to receive said float.

4. The combination set forth in claim 2, a valve seat in said evacuating conduit, a float within said evacuating conduit having an upper portion shaped to seat in said valve seat, a lower portion of low density and a central portion constituted by said perforated means.

5. The combination set forth in claim 2, a valve seat in said evacuating conduit, a float valve means within said evacuating conduit adapted to seat in said valve seat, said float valve having said perforated means mounted thereon, the clearance between the walls of said evacuating conduit and said float valve means being small whereby said perforated means may be positioned close to said hole.

ERNST LOREN WALLESER.
